UNITED STATES PATENT OFFICE.

BENJAMIN H. STEVENSON, OF HAMLER, OHIO.

HYDRAULIC TRANSMISSION FOR AUTOMOBILES.

976,226.

Specification of Letters Patent. Patented Nov. 22, 1910.

Application filed September 27, 1909. Serial No. 519,677.

To all whom it may concern:

Be it known that I, BENJAMIN H. STEVENSON, a citizen of the United States, residing at Hamler, in the county of Henry, State of Ohio, have invented certain new and useful Improvements in Hydraulic Transmission for Automobiles; and I do hereby declare the following to be a full, clear, and exact description of the invention, such as will enable others skilled in the art to which it appertains to make and use the same.

This invention relates to automobiles and has special reference to a drive for such devices.

15 The invention furthermore refers more especially to a mechanism for the hydraulic transmission of power from the engine to the drive shaft.

20 One object of the invention is to provide an improved means for the transmission of power by hydraulic apparatus from the engine to the drive shaft of the automobile.

25 Another object of the invention is to provide an improved means for controlling the speed of the automobile, the control being obtained while the engine runs at uniform speed by the variation in the amount of fluid transmitted.

30 A third object of the invention is to provide a mechanism of this character wherein a constant circulation of liquid will be obtained during the entire time the engine is running.

35 A fourth object of the invention is to provide an improved reversing mechanism for an engine of this character.

40 A fifth object of the invention is to provide an improved reversing valve for use with such mechanism.

45 With the above and other objects in view the invention consists in general of an engine, preferably of the multi-cylinder type, each cylinder of the engine being directly connected to a pump, in combination with a source of fluid supply, certain valve mechanism, and a driving mechanism for the driving axle.

50 The invention further consists in certain novel details of construction and combinations of parts hereinafter fully described, illustrated in the accompanying drawings, and specifically set forth in the claims.

55 In the accompanying drawings, like characters of reference indicate like parts in the several views, and:—Figure 1 is a side elevation of an automobile chassis equipped

with this invention. Fig. 2 is a plan view thereof. Fig. 3 is a detail transverse section through one of the engine cylinders showing the valve arrangement therefor. Fig. 4 60 is a section on the line 4—4 of Fig. 3. Fig. 5 is a section on the line 5—5 of Fig. 3. Fig. 6 is an enlarged detail view of the drive motor which actuates the transmission gearing for the rear shaft. Fig. 7 is an enlarged 65 detail sectional view through the starting and stopping valve. Fig. 8 is a detail view of the valve removed from its casing, the view being at right angles to Fig. 7. Fig. 9 is an end view of this valve. Fig. 10 is 70 an enlarged detail section through the reversing valve. Fig. 11 is a section on the line 11—11 of Fig. 10. Fig. 12 is a section through the steering post showing the valve controlling device. Fig. 13 is a view on the 75 line 13—13 of Fig. 10. Fig. 14 is a section on the line 14—14 of Fig. 6. Fig. 15 is a view of a form of transmission gear adapted to be used with this invention.

The automobile here shown is provided 80 with the usual rear wheels 20 and front wheels 21 and the rear wheels are mounted on an axle 22 which constitutes the drive axle in the present instance, while the front wheels are mounted on knuckles 23. 85

At 24 is a steering post and this steering post is in the form of a tube to which is securely fastened a steering wheel 25 and which is connected by suitable mechanism to the knuckles of the front wheels as indicated at 26, it being understood that this mechanism is merely typical of any preferred form and that detail description is not deemed necessary. 90

95 Mounted on the chassis is an engine which is here indicated as a six cylinder engine and this engine is of the usual internal combustion type. Each cylinder of the engine comprises a combustion chamber 27 wherein moves a piston 28. These combustion chambers are each provided with the usual valve inlet 29 and valve outlet 30 as well as with some form of sparking plug as indicated at 31. The cylinder forming the combustion chamber has around the lower end thereof 100 a broad flange 32 whereto is secured a cylinder 33 provided with oppositely disposed guides 34. Connected to the piston 28 is a rod 35 whereon is mounted a cross head 36 provided with fork ends 37 which fit the 105 guides 34. This cross head is furthermore provided with an opening 38 extending sub-

stantially the entire length of the cross head between the fork ends 37 and in this opening slides a crank block 39. This block 39 slides freely in the opening 38 and is provided with oppositely disposed trunnions 40. At 41 is a crank shaft whereon are crank arms 42 the free ends of which engage the trunnions 40. Now, it will be observed that as the explosion takes place the parts just described form what is commonly known in mechanics as a slider crank. Where more than one cylinder is employed the cranks will be set at angles to each other as is common in devices of this character so that the explosions in the cylinders will take place one after the other according to the number of cylinders employed.

Secured to the lower end of the cylinder 33 is a pump cylinder 43 having a wide flange 44 to enable it to be attached to the cylinder 33 and this pump cylinder contains a valveless piston 45 which is connected to the cross head 36 by means of a piston rod 46. Attached to the lower end of the pump cylinder 43 is a valve casing 47 and the pump cylinder is provided with an outlet port 48 wherein is held an outlet valve 49. The pump cylinder is furthermore provided with an inlet port 50 which is controlled by an inlet valve 51. The outlet valve 49 is provided with a stem 52. Surrounding the stem 52 is a spring 53 the lower end of which rests against the valve casing while the upper end bears against the outwardly opening valve 49 so that this valve is normally held closed by the action of the spring 53. The valve 51 is provided with a stem 54 and on this stem is a collar 55. Surrounding the stem is a spiral spring 56 one end whereof bears against the collar 55 while the other end bears against the lower end of the cylinder 43. In this manner the inlet valve is normally held closed.

At 57 is a tank which contains a suitable fluid which will be referred to throughout this specification as water although it is obvious that oil or some non-freezing liquid may be used. Extending from the tank 57 to the inlet side of the valve casing 47 is a pipe 58 and extending from the outlet side of the valve casing is a pipe 59. The pipe 59 leads to a valve casing 60 which is provided with a cap 61. This valve casing is enlarged at the center to form a valve chamber 62 provided with a suitable valve seat 63 against which a valve 64 is adapted to rest when the device is in running position. The cap 61 is likewise provided with a valve seat 65 against which the valve 64 is adapted to rest when the device is in the position in which no power is transmitted to the rear axle. This valve is of peculiar construction and comprises a cylindrical body terminating in frusto-conical ends 66 to conform to the valve seats 63 and 65 and beyond these

frusto-conical ends are further cylindrical portions 67 of less diameter than the body and having through slots 68 opening outward from each end. Connected to the same end of the valve casing 60 as the pipe 59 is a pipe 69 which leads back to the tank 57. Now, it will be observed that when the engine is running the pump cylinder 43 will be filled with water drawn through the inlet valve as the piston rises and this water will be driven out through the outlet valve as the piston falls. Now if the valve 64 be so positioned that it rests against the valve seat 65 the water will flow through the pipe 59 and into the chamber 62 from whence it will escape through the slot 68 at one end of the valve to the pipe 69. It will thus be returned to the tank without having performed any useful work. Connected to the cap is a pipe 70 which is in turn connected to a reversing valve casing 71 which is divided intermediate its ends by a septum 72 having a perforation 73 in the center thereof. On each side of the septum 72 is a piston 74 and these pistons are mounted on a valve stem 75 which projects through a stuffing box 76 at one end of the valve casing 71. On the same side of the septum as that into which the pipe 70 opens is a port 77 wherfrom a pipe 78 leads to a motor casing 79 surrounding the rear axle 22. Within the motor casing and projecting through one side thereof is a sleeve 80 whereto is fixed a main drive gear of a train of differential gearing typically indicated at 81. Mounted inside of the casing 79 on the sleeve 80 is a hub 82 whereto is connected a series of impact turbine blades or buckets 83 and the pipe 78 opens into the casing 79 at the proper angle to strike these blades or buckets. Extending from the casing 79 at the opposite angle to the pipe 78 is a pipe 84 which opens through a port 85 into the valve casing 71 on the side of the septum opposite the port 77. On the same side as the port 85 is a second port 86 with which communicates a pipe 87 which returns to the tank 57 and opens therein through a port 88. The pipe 78 also communicates with the rear portion of the valve casing by means of a port 89 while the pipe 84 communicates with the forward portion of the valve casing by means of a port 90. Now, referring to Fig. 11, if the pistons be positioned as indicated in dotted lines in that figure water will enter as the engine works, if the valve 64 is open, through the pipe 70 into the valve chamber and from there will flow out through the port 77 into the pipe 78 and will cause the motor to be rotated in the direction of the arrow in Fig. 6. The returning water will flow through the pipe 84 and enter through the port 85. This water will then pass out through the pipe 87 and return to the tank 57 to be used

again. If, however, the pistons be positioned as shown in full lines in Fig. 11 the water coming in through the pipe 70 will flow out through the port 90 and enter the 5 motor chamber through the pipe 84 thus running the engine in the opposite direction. From the motor chamber it will flow through the pipe 78 and enter the valve casing 10 through the port 89 whence it will escape as previously described, through the pipe 87 and return to the tank 57. It will thus be observed that by proper adjustment of the 15 pistons the drive motor may be caused to rotate in either direction, as desired. Furthermore, by regulating the position of the 20 valve 64 more or less of the water may be caused to pass through the pipe 70 so that a greater or less force may be exerted on the motor.

20 In order to provide for the controlling of the reversing valve there are mounted on the chassis suitable brackets 91 through which passes a threaded portion 92 of the valve stem 75 and on this threaded portion is held 25 a bevel gear 93 threaded to properly fit this portion of the stem.

Within the sleeve 24 is rotatably mounted a sleeve 94 upon the upper end of which is an operating handle 95 while upon the lower 30 end of this sleeve is carried a segmental gear 96 which meshes with the gear 93. Now, by properly positioning the handle 95 the segmental gear will be caused to revolve in one direction or the other and as the gear 35 93 rotates it will act as a stationary nut for the threaded portion 92 of the stem 75 and will thus cause the piston 74 to take position either as shown in full or as shown in dotted lines.

40 In order to operate the valve 64 the same is provided with a stem 97 which projects through a stuffing box 98 and is provided with a threaded portion 99. Mounted on the chassis are brackets 100 through which 45 passes the threaded portion 99 and between these brackets on this threaded portion is held a threaded gear 101 similar to the gear 93. In order to rotate this gear 101 there is 50 mounted within the sleeve 94 a rod 102 having at its upper end an operating handle 103 while upon its lower end is mounted a beveled segment 104. The operation of this 55 valve is precisely similar to that of the reversing valve, that is to say, by turning the handle 103 in one direction or another, as the case may be, the position of the valve 64 can be accurately adjusted.

60 In the operation of the entire device the valve 64 is first positioned so that it closes the pipe 70. The engine is then started and as soon as circulation has been established between the pipes 59 and 69, the piston 74 having been properly positioned meanwhile, the 65 valve 64 is moved to open the pipe 70 and this results in throttling the flow through

the pipe 69. The automobile is thus started without shock and the valve 64 may be slowly closed with reference to the pipe 69 until the full force of the engine is filling the motor casing. In stopping the automobile 70 it is merely necessary to shut off the flow through the pipe 70 when the automobile will stop of its own accord, or if a sudden stop be desired, the position of the reversing valve may be changed to throw the fluid 75 pressure in the opposite direction through the motor chamber.

There has thus been provided a simple and efficient device of the kind described and for the purpose specified.

Having thus described the invention, what is claimed as new, is:—

1. In an automobile power transmission, a reversing valve, comprising a casing having a septum thereacross to divide the casing 85 into front and rear chambers, the front chamber being provided with an inlet port and a pair of outlet ports lying on opposite sides of the inlet port, and said rear chamber being provided with an outlet port and pair of 90 inlet ports lying on opposite sides of the outlet port, a piston valve in each chamber, and a valve stem connecting said pistons whereby the pistons may be reversed to lie on either side of the central ports of the respective chambers. 95

2. In an automobile power transmission, a reversing valve comprising a casing having a septum thereacross to divide the casing into front and rear chambers, the front chamber being provided with an inlet port and a pair of outlet ports lying on opposite sides of the inlet port, the rear chamber being provided with an outlet port and a pair of 100 inlet ports lying on opposite sides of the outlet port, a piston valve in each chamber, a valve stem connecting said pistons whereby the pistons may be moved to lie on either side of the central ports of the respective chambers, a reversible motor, and pipes connecting the end ports of said chambers with 105 said motor. 110

3. The combination with an automobile having a steering post; of a reversing valve, comprising a casing having a septum thereacross to divide the casing into front and rear chambers, the front chamber being provided with an inlet port disposed centrally of said chamber and a pair of outlet ports lying on opposite sides of said inlet port at the ends of said chamber, the rear chamber being provided with a centrally disposed outlet port and a pair of inlet ports lying on opposite sides of the outlet port at the ends of said rear chamber, a piston valve in each chamber, a valve stem connecting said pistons whereby the pistons may be reversed to lie on either side of the central ports of the respective chambers, means on the steering post operatively connected to said valve 115 120 125 130

stem, a reversible motor, and pipes connecting the end ports of said valve chambers with said motor.

4. The combination with an automobile 5 having a steering post; of a reversing valve, comprising a casing having a septum there-across to divide the casing into front and rear chambers, the front chamber being pro- 10 vided with an inlet port disposed centrally of said chamber and a pair of outlet ports lying on opposite sides of said inlet port at the ends of said chamber, the rear chamber being provided with a centrally disposed outlet port and a pair of inlet ports lying 15 on opposite sides of the outlet port at the ends of said rear chamber, a piston valve in each chamber, a valve stem connecting said pistons whereby the pistons may be reversed to lie on either side of the central ports of 20 the respective chambers, means on the steering post operatively connected to said valve stem, a reversible motor, pipes connecting the end ports of said valve chambers with said motor, an engine, a pump actuated by 25 said engine, and pipes leading from said pump to the central ports of said chambers.

5. The combination with an automobile having a steering post; of a reversing valve, comprising a casing having a septum there-

across to divide the casing into front and 3 rear chambers, the front chamber being pro- vided with an inlet port disposed centrally 3 of said chamber and a pair of outlet ports lying on opposite sides of said inlet port at the ends of said chamber, the rear chamber being provided with a centrally disposed outlet port and a pair of inlet ports lying 4 on opposite sides of the outlet port at the ends of said rear chamber, a piston valve in each chamber, a valve stem connecting said 4 pistons whereby the pistons may be reversed to lie on either side of the central ports of the respective chambers, means on the steering post operatively connected to said valve 5 stem, a reversible motor, pipes connecting the end ports of said valve chambers with said motor, an engine, a pump actuated by said engine, pipes leading from said pump to the central ports of said chambers, valve means in one of the last mentioned pipes, and means on said steering post operatively connected to said valve means.

In testimony whereof, I affix my signature, in presence of two witnesses.

BENJAMIN H. STEVENSON.
